UNITED STATES PATENT OFFICE.

WILLIAM R. JEAVONS AND ARNOLD R. WHITTAKER, OF CLEVELAND, OHIO.

OIL-BURNER.

1,143,199.

Specification of Letters Patent. Patented June 15, 1915.

Application filed July 10, 1912. Serial No. 708,599.

To all whom it may concern:

Be it known that we, WILLIAM R. JEAVONS and ARNOLD R. WHITTAKER, citizens of the United States, residing at Cleveland, in the county of Cuyahoga and State of Ohio, have invented a certain new and useful Improvement in Oil-Burners, of which the following is a full, clear, and exact description, reference being had to the accompanying drawings.

This invention relates to oil burners of the type wherein there is a pair of wick tubes and an air distributor having a spreader extending across and spaced from the top of the wick tubes, the inner wick tube being provided with a seat for the distributor, formed preferably as a spanner comprising an outer and an inner ring and connected by arms, the inner ring having a central guide opening for the spindle which depends from the central portion of the distributor.

As heretofore constructed, the distributor has been supported by means of a spreader of the character hereinbefore described having a vertically extending annular flange at its periphery, which flange has been secured to the inner tube by means of solder. In operation, the parts are liable to be so subjected to heat as to melt the solder, with the result that the support for the distributor will become dislodged, leaving the distributor with no means for supporting and centering the same. In burners of this type it is exceedingly important that the spreaders shall be at a predetermined distance from the tops of the wick tubes. Should the support for the distributor, of which the spreader forms a part, become loosened or have its position altered in a vertical direction, the distance between the spreader and the tops of the wick tubes would be correspondingly affected with the result that the burner will not properly function.

It is the purpose of this invention to provide an extremely efficient, though simple, means whereby the distributor support or spanner may be anchored securely in place within the inner wick tube without any liability to become dislodged.

With the foregoing objects in view the invention may be defined further and more generally as consisting of the combinations of elements embodied in the claims hereto

annexed and illustrated in the drawings 55 forming a part hereof, wherein—

Figure 1 represents a vertical sectional view taken through a portion of the oil stove burner, illustrating the manner of supporting the spanner within the inner wick tube; Fig. 2 represents a transverse sectional view taken through the inner wick tube of the aforesaid burner and showing the projections whereby the distributor support is anchored in place, the view being taken on 65 approximately the line 2—2 of Fig. 3; Fig. 3 represents an elevation of the portion of the inner wick tube which is provided with the anchoring projections, and Fig. 4 an enlarged sectional detail illustrating the 70 manner in which the outer edge of the distributor support is held in place.

Describing the various parts illustrated herein by means of reference characters, 1 represents the inner and 2 the outer wick 75 tube of a burner, said tubes having interposed therebetween a wick 3, which may be raised and lowered by means of a wick raising shaft having an operating handle 4.

Within the interior of the inner wick tube 80 there is located an air distributor and spreader, which is of the type shown in the patent to Jeavons No. 871,593 issued November 19, 1907. This combined air distributor and spreader comprises a ring 5 having perforations at the upper end thereof, the ring being connected to a neck 6, to the top of which are attached the spreader plates 7 and 8. The spindle 9 is connected to the upper spreader plate and depends centrally therefrom within the neck 6 and ring 5. Depending from the bottom of the distributor and spreader is a locking device having depending horizontal shoulders 11 which normally extend beneath the arms 12 of the spider. 95 The vertical movement of the distributor and spreader will be limited by the engagement of the shoulders 11 with the arms 12, in the manner described at length in the patent referred to.

The arms 12 of the spanner connect the central ring or annular plate 13 with the outer ring or annular supporting plate 14. The inner ring is provided with an aperture 15 for the reception of the spindle 9. 105 The outer edge of the ring 14 is in substantial engagement with the inner surface of the inner wick tube and is supported

- therein by means of an upper and a lower series of inwardly extending projections pressed from the body of the wick tube. The upper series of projections 16 and the lower series of projections 17 are preferably formed in the wick tube after the spider is inserted in place, the two series being vertically spaced to receive snugly therebetween the outer edge of the supporting ring or plate 14 (see particularly Fig. 4). In forming these projections in the light sheet metal of which the inner wick tube is composed, there is great danger that the metal will be so drawn or stretched as to afford an insecure support for the distributor support, if, in fact, the support is not allowed to drop by reason of the stretching action referred to. To avoid stretching the metal to this extent and at the same time to provide a very secure anchoring means for the distributor support, the projections in each series are spaced laterally a considerable distance apart,—greater than the width of a projection (or the width of the recess caused by forming a projection)—and the projections of one series are staggered with respect to those of the other series. This arrangement will be clear from Fig. 3. The projections may be conveniently formed by means of two toothed wheels placed side by side on a common arbor, or by a double toothed wheel, the teeth being of such width and so spaced as to provide the arrangement of projections shown in the drawings.
- The anchoring means described herein is one obtainable in an extremely simple manner and may be produced at very small expense. It has, however, been found to be extremely efficient in use.
- Having thus described our invention, what we claim is:
1. In an oil burner, the combination, with a cylindrical metal tube adapted to form the internal support for a circular wick, of a supporting member located within said tube and engaging the walls thereof, said tube being provided with an upper and a lower series of circularly spaced projections extending inwardly from the inner wall thereof above and below the outer edge of said supporting member.
  2. In an oil burner, the combination, with a cylindrical metal tube adapted to form the internal support for a wick, of a supporting member located within said tube and having its outer edge abutting against the interior of the tube wall, said tube having an upper and a lower series of circularly spaced projections located above and below the outer edge of said supporting member, said projections being formed by pressing inwardly the metal of the tube wall and the projections in one series being staggered with respect to those in the other series.
  3. In an oil burner, the combination, with a cylindrical thin metal tube adapted to form the internal support for a wick, of a supporting member located within said tube and having its outer edge abutting against the interior wall of said tube, said tube having an upper and a lower series of circularly spaced internal projections formed by embossing the metal of the tube and receiving between them the outer edge of said supporting member, the distance between adjacent projections of each series being greater than the width of a projection, and the projections of one series being staggered with respect to those of the other series.
  4. In an oil burner, the combination, with a cylindrical metal tube adapted to form an inner wick tube, of a supporting member or spanner of substantially the same external diameter as the internal diameter of said tube and adapted to engage said tube with its outer edge, said tube being provided with an upper and a lower series of circularly spaced projections extending inwardly from the inner wall thereof above and below the outer edge of said supporting member or spanner, the distance between adjacent projections of each series being greater than the width of a projection.

In testimony whereof, we hereunto affix our signatures in the presence of two witnesses.

WILLIAM R. JEAVONS.
ARNOLD R. WHITTAKER.
